TAMPING ROLLER

Marvin E. Whiteman, Los Angeles, Calif.

Application August 11, 1941, Serial No. 406,319

3 Claims. (Cl. 94—50)

This invention relates to a tamping roller for tamping freshly poured concrete.

An object of the invention is to provide a roller that can be rolled over freshly poured concrete which will be subjected during its rolling movement to the effects of a series of downward blows effectively applied to the roller thus serving to settle the concrete and to work the fine portions thereof or the float to the surface. The float on being worked to the surface may thereafter be trowelled or finished if desired.

Heretofore, tamping devices of this general character have been devised employing rotary eccentric weights within the roller having a tendency during rotation to vibrate the roller. The vibrational movement created by the eccentric weights is in all directions so that some of the effectiveness of the eccentric weight is to tend to lift the roller from the concrete which is not desired. By means of the present invention the effects of a series of downwardly blows are transmitted to the roller to effectively tamp the concrete without the generation of any air pockets therein.

With the foregoing and other objects in view, which will be made manifest in the following detailed description and specifically pointed out in the appended claims, reference is had to the accompanying drawings for an illustrative embodiment of the invention, wherein:

Figure 1 is a vertical section through an improved tamping roller embodying the present invention;

Fig. 2 is a partial horizontal section taken substantially upon the line 2—2 upon Fig. 1;

Fig. 3 is a view in end elevation of the tamping roller embodying the present invention;

Fig. 4 is a sectional view taken substantially upon the line 4—4 upon Fig. 3;

Fig. 5 is a sectional view taken substantially upon the line 5—5 upon Fig. 2; and

Fig. 6 is a vertical section taken substantially upon the line 6—6 upon Fig. 5.

Referring to the accompanying drawings wherein similar reference characters designate similar parts throughout, the improved tamping roller comprises a suitable handle 10 preferably formed of pipe so as to be hollow. Attached to this handle is a U-shaped fork 11 preferably formed of channel iron. In the arms of the fork there are secured bushings 12 within which are mounted hollow trunnions 13 attached to the end walls 14 of an internal frame or housing. The trunnions 13 serve to rotatably mount the end wheels 15 of the tamping roller. These end

wheels are preferably connected by longitudinally extending bars 16 which in turn are connected intermediate the end wheels by rings 17. The end wheels, rings, and bars are surrounded with an outer roller covering which in the preferred form of construction comprises woven wire screen 18.

The end walls 14 of the internal housing are connected by longitudinally extending angle irons 19 and by an outer covering 20. The angle irons 19 serve as a motor mount for an electric motor 21 which has a driving connection such as by a belt drive 22 with a cam shaft 23. The cam shaft 23 is supported in bearings 24 in cam cases 25 which are likewise supported on the angle irons 19, see Fig. 6. On the ends of the cam shaft and within the cam cases there are keyed cams 26 which are spiral in form having high points 27 and low points 28. The tops of the cam cases provide cylinders 29 within which are reciprocable cam followers 30 which are urged downwardly by means of coil springs 31 compressed between cam followers and cylinder caps 32. Stems 33 slidably extend through the caps and are attached to the cam followers and carry heads 34 constituting hammers. The hammers are adapted to be lifted by the cams 26 through cam followers 30 and stems 33 and when the high points 27 pass from beneath the cam followers that are allowed to drop with the result that the heads or hammers 34 impart downwardly directed blows to the anvils or cylinder caps 32.

On the handle 10 there is preferably a switch box 35 to which a cord 36 is connected. Wiring 37 leads from the switch box 35 through the handle and along the interior of the fork 11 through a tubular trunnion 13 and to the electric motor 21.

When the concrete C is freshly poured the roller may be manipulated thereover by means of the handle 10 during which manipulation the electric motor 21 is driven to drive the cam shaft 23 lifting the hammers and releasing them to impart downward blows to the caps 32. The effects of these downward blows are transmitted through the angle irons 19 and the end walls 13 to the hubs of the wheels 15 that surround the hollow trunnions 13. Thus during manipulation of the roller there is imparted thereto a succession of downward tamping blows that tend to settle the concrete and work the float toward the surface. The cams 26 may be so arranged on the cam shaft as to cause the hammers illustrated to be operated in sequence. However, any suitable arrangement of the cams may be em-

ployed which will cause the hammers to be operated individually, in pairs, or simultaneously.

It will thus be appreciated that by means of the improved tamping roller there is provided a means for imparting a succession of downward blows that will be effectively transmitted to the roller to bring about a good tamping of the freshly poured concrete.

Various changes may be made in the details of construction without departing from the spirit or scope of the invention as defined by the appended claims.

I claim:

1. A concrete tamper comprising a roller, a frame suspended from trunnions in said roller, a handle connected to the trunnions, the center of gravity of said frame being below the axis of said trunnions, a cam shaft on said frame, a plurality of spring actuated hammers on the frame arranged to be lifted by the cam shaft and allowed to fall under the actions of their springs, and means for rotating the cam shaft whereby a series of downwardly directed im-

pulses will be created by the hammers and transmitted to the roller.

2. A concrete tamper comprising a roller, a frame within the roller, a handle for the roller, means connecting the handle and the frame supported by said roller, a cam shaft on the frame, spring actuated hammers above the cam shaft arranged to be lifted and allowed to fall under the actions of their springs, and means for rotating the cam shaft whereby the hammers will create and impart a series of downwardly directed impulses to the frame which will be transmitted to the roller.

3. A concrete tamper comprising a roller, a frame within the roller, a handle for the roller, means connecting the handle and the frame so as to be capable of holding the frame against rotation with the roller, said means being supported by the roller, and vibrating means on the frame for creating a series of downwardly directed impulses thereto which will be transmitted to the roller.

M. E. WHITEMAN.
